UNITED STATES PATENT OFFICE.

ROBERT H. YURGAE, OF MILWAUKEE, WISCONSIN, ASSIGNOR TO SIGNAL PHONE COMPANY, OF MILWAUKEE, WISCONSIN.

TELEPHONY.

SPECIFICATION forming part of Letters Patent No. 728,350, dated May 19, 1903.

Application filed November 24, 1902. Serial No. 132,536. (No model.)

To all whom it may concern:

Be it known that I, ROBERT H. YURGAE, a citizen of the United States, and a resident of Milwaukee, in the county of Milwaukee and 5 State of Wisconsin, have invented certain new and useful Improvements in Telephony; and I do hereby declare that the following is a full, clear, and exact description thereof.

My invention relates to electric-telephone systems in which provision is had for direct calling and talking connection of any one with any other station of the same system, the object of this invention being to organize the telephone apparatus at each station with 10 reference to the utilization of the receiver-hanger as a circuit-controller, this hanger being automatically and manually adjustable from normal position to which it has automatic return from any adjusted position when 15 the receiver is hung thereon. Hence said invention consists in what is hereinafter particularly set forth with reference to the accompanying drawings and subsequently claimed.

Figure 1 of the drawings represents a front elevation of telephone apparatus in accordance with my invention, parts being removed and in section, the receiver-hanger being shown in normal position by dotted lines and 20 in a manually-adjusted position by full lines; Fig. 2, a side elevation of said apparatus, partly in section, said receiver-hanger being in the adjusted position shown in the first figure; Figs. 3, 4, and 5, detail sectional views 25 respectively indicated by lines 3, 4, 4, and 55 in said first figure; Fig. 6, a detail front elevation illustrating the receiver on hanger and a pointer in connection with said hanger to move therewith opposite an adjacent stationery index, and Fig. 7 a diagram illustrating carrying out of my invention.

Referring by letter to the drawings, A indicates the transmitter, B the induction-coil, C the receiver, and D the audible signal device, of a telephone apparatus, this signal device in the present showing being an electric bell. The telephone apparatus herein shown also includes a push-button E, by which to close a calling-circuit; but other means suitable for the same purpose may be substituted. The receiver-hanger F of the telephone ap-

paratus is shown in sliding connection with a vertical rod G, set in a box H, attached to the front of a wall-piece I, and this box is provided with a vertical side recess in which 55 said hanger has play. A lateral stud b of the receiver-hanger extends through a vertical slot in the preferably removable front of box H, and held on a shouldered portion of the stud by a nut c is a horizontal pointer J, that 60 moves parallel to said box-front opposite an index thereon that corresponds to a plurality of spring-contacts in an electric switch that also comprises a vertical conductor-bar K, facing said contacts. The index is preferably a series of numbers, and said spring-contacts are herein indicated by similar numbers, each of these contacts being in electric connection with a similar element of the switches at the other stations in the system, 65 binding-posts being provided at each station for the connections.

The shank portion of the receiver-hanger is partly in the form of a shell containing antifriction-rollers d, arranged to bear against 75 the rod G, this rod being full round for the greater portion of its length, but slabbed at the lower end, as shown in Fig. 4. A leaf-spring e, fast at one end to the hanger-shank, is provided with a lug f, that extends through 80 the shell portion of said shank to be at times in frictional contact with rod G, and thereby clutch the hanger in adjusted position on the full round portion of said rod. The other bent end of spring e engages a side recess in 85 the receiver-hanger shank and abuts the inner end of a bolt g, loose in said shank. The outer end of the bolt is in the way of the receiver C, and a lug h of said bolt has play in 90 a slot longitudinally of the receiver-hanger. The receiver being off hanger and the latter clutched on rod G, return of said receiver to the hanger will retract the bolt to unclutch 95 said hanger and permit automatic return of same to normal position.

Depending from the receiver-hanger is an insulation-lug i, and a spring-contact j in the path of this lug is for electrical connection with a battery or other source of electrical energy, this contact being fast at one end to 100 an insulation-block L on the bottom of the box aforesaid. Other contacts k m n, arranged

on the insulation-block, are respectively for electrical connection with signal D and the primary and secondary of coil B, above specified. When there is pressure of hanger-lug 5 *i* on contact *j*, due to the hung-up receiver, said contact is away from the ones *m n* and on the one *k*; but said receiver being taken off hanger there is automatic recoil of contact *j* from the contact *k* to close on the contacts *m n*, there being corresponding automatic lift of the receiver-hanger F on the slabbed portion of rod G, above specified.

The inner end of the receiver-hanger carries insulation, preferably in the form of a 15 roller *p*, that operates by adjustment of said hanger to move some one of the aforesaid spring-contacts in the numerically-indicated series against bar K of the electric switch that is common to the calling and talking 20 circuits of all the telephone-stations in the system, said contacts and bar of the switch being fast on an insulating-block M in the box H aforesaid.

The electrical connections at each telephone-station are such with respect to the 25 numerically-indicated spring-contacts and bar K of the electric switch that any other telephone-station in the same system can be called direct subsequent to the taking of the receiver at the calling-station off hook to permit shift of spring-contact *j* from contact *k* to contacts *m n*, whereby the signal at said calling telephone-station is cut out and the induction-coil at the same station cut in, a 30 like result occurring at the called station when receiver thereat is taken off hanger. The lower one of the numerically-indicated spring-contacts at each station is normally in touch with the opposing bar K, and its number 35 agrees with that of said station.

Referring particularly to the diagram Fig. 7, the receiver at telephone-station No. 1 is off hanger, and the hanger itself has been manually adjusted to put spring-contact 2 into touch with switch-bar K, from which spring-contact *l* has recoiled, contact *j* having in the meantime shifted from contact *k* to contacts *m n*, so if there be manipulation 45 of push-button E the result will be a call at 50 station No. 2, the calling-circuit tracing from said push-button to one side of battery N, through the battery to contact *j* at No. 2 station, through bell D at this station, and back through the intercommunicating switch at 55 No. 1 station to said push-button. No. 2 station having been called and the receiver thereat taken off hanger, this hanger will be lifted by shift of spring-contact *j* at the same station from opposing call-circuit contact *k* 60 to opposing induction-coil contacts *m n*; but spring-contact 2 at this station remains in touch with the opposing switch-bar K, there being clearance at the lower end of rod G, as above described, to prevent clutching of said 65 hanger thereon, except when manually adjusted to force some one of the other numerically-indicated spring-contacts into touch

with said bar. A talking-circuit will now be established between the stations aforesaid, and from one side of the transmitter at each 70 station the circuit can be traced to the battery, through the same to contact *j* and induction-coil B, back to the other side of said transmitter, and from one side of each receiver circuit can be traced through open 75 push-button and intercommunicating switch at the same station, thence on to the intercommunicating switch, open push-button, receiver, coil, and spring-contact *j* at the other station, back on one side of the battery, and through contact *j* and coil at the starting-station into the other side of the receiver at which the trace began.

The telephone system is a common return 85 system with a single source of electrical energy for both calling and talking purposes; but the intercommunicating apparatus set forth as employed at each station may be utilized in various well-known telephone systems.

Having thus described my invention, what I claim as new, and desire to secure by Letters Patent, is—

1. An electric-telephone apparatus comprising call-sending and call-receiving mechanism, a transmitter, receiver, induction-coil and switch; the switch consisting of a main contact and a series of spring-contacts opposed thereto, each spring-contact being for electric connection with a like element in a switch constituting part of electric-telephone apparatus similar to that aforesaid at each of a plurality of stations in the same system, the main contact being electrically connected to be alternately in calling or talking circuit at its own station, an insulated movable hanger that in normal position closes one of said spring-contacts against said main contact, manual adjustment of the hanger serving to clear this spring-contact and close another in the series against the aforesaid main contact, said hanger being returned to normal position from any adjustment by weight of the telephone-receiver hung thereon, and means co-operative with said hanger to control alternate cutting in and out of the telephone call-signal and induction-coil.

2. An electric-telephone apparatus comprising call-sending and call-receiving mechanism, a transmitter, receiver, induction-coil and switch; the switch consisting of a main contact and a series of spring-contacts opposed thereto, each spring-contact being for electric connection with a like element in a switch constituting part of electric-telephone apparatus similar to that aforesaid at each of a plurality of stations in the same system, the main contact being electrically connected to be alternately in calling or talking circuit at its own station, an insulated movable hanger that in normal position closes one of said spring-contacts against said main contact, manual adjustment of the hanger serving to clear this spring-contact and close

- another in the series against the aforesaid main contact, said hanger being returned to normal position from any adjustment by weight of the telephone-receiver hung thereon, means coöperative with said hanger to control alternate cutting in and out of the telephone call-signal and induction-coil, an index for the spring-contacts aforesaid, and an index-pointer carried by the hanger.
5. An electric-telephone apparatus comprising call-sending and call-receiving mechanism, a transmitter, receiver, induction-coil and switch, the switch consisting of a main contact-piece and a series of spring-contacts opposed thereto, each spring-contact being for electric connection with a like element in a switch constituting part of an electric-telephone apparatus similar to that aforesaid at each of a plurality of stations in the same system, the 70 main contact being electrically connected to be alternately in calling or talking circuit at its own station, an insulated movable hanger that in normal position closes one of said spring-contacts against said main contact, 75 manual adjustment of the hanger serving to clear this spring-contact and close another in the series against the aforesaid main contact, mechanism with the hanger automatically operative to clutch the same in manually-adjusted position when the telephone-receiver is removed therefrom, there being automatic release of the clutch mechanism and return of said hanger to normal position from any 80 adjustment when the receiver is hung thereon, and means coöperative with the aforesaid hanger to control alternate cutting in and out of the telephone call-signal and induction-coil.
10. 3. An electric-telephone apparatus comprising call-sending and call-receiving mechanism, a transmitter, receiver, induction-coil and switch, the switch consisting of a main contact and a series of spring-contacts opposed thereto, each spring-contact being for electric connection with a like element in a switch constituting part of electric-telephone apparatus similar to that aforesaid at each of a plurality of stations in the same system, the 85 main contact being electrically connected to be alternately in calling or talking circuit at its own station, an insulated movable hanger that in normal position closes one of said spring-contacts against said main contact, 90 manual adjustment of the hanger serving to clear this spring-contact and close another in the series against the aforesaid main contact, mechanism with the hanger automatically operative to clutch the same in manually-adjusted position when the telephone-receiver is removed therefrom, there being automatic release of the clutch mechanism and return of said hanger to normal position from any 95 adjustment when the receiver is hung thereon, and means coöperative with the aforesaid hanger to control alternate cutting in and out of the telephone call-signal and induction-coil.
15. 4. An electric-telephone apparatus comprising call-sending and call-receiving mechanism, a transmitter, receiver and switch, the switch consisting of a main contact and a series of spring-contacts opposed thereto, each spring-contact being for electric connection 100 with a like element in a switch constituting part of electric-telephone apparatus similar to that aforesaid at each of a plurality of stations in the same system, the main contact being electrically connected to be alternately in calling or talking circuit at its own station; a vertical rod, an insulated hanger in sliding engagement with the rod and which in normal position closes one of said spring-contacts against said main contact, manual adjustment of the hanger on said rod serving to 105 clear this spring-contact and close another in the series against the aforesaid main contact, means with the hanger for automatically clutching the same in manually-adjusted position when the telephone-receiver is removed therefrom, there being automatic unclutch of said hanger and automatic return of same to normal position from any adjustment when said receiver is hung thereon, and means coöperative with the aforesaid hanger to control alternate cutting in and out of the telephone call-signal and induction-coil.
20. 5. An electric-telephone apparatus comprising call-sending and call-receiving mechanism, a transmitter, receiver, induction-coil and switch, the switch consisting of a main contact-piece and a series of spring-contacts opposed thereto, each spring-contact being for electric connection with a like element in a switch constituting part of an electric-telephone apparatus similar to that aforesaid at each of a plurality of stations in the same system, the main contact being electrically connected to the call-sending mechanism at its own station, an insulated movable hanger that in normal position closes one of said spring-contacts against said main contact, manual adjustment of the hanger serving to clear this spring-contact and close another in the series against the aforesaid main contact, 110 this hanger being returned to normal position from any adjustment by weight of the telephone-receiver hung thereon, a contact constituting part of the call-receiving circuit, other contacts in electric connection with the primary and secondary of the induction-coil, a line-terminal spring-contact arranged between the call-circuit and induction-coil contacts, and an insulation-lug with the receiver-hanger that normally holds the line-terminal contact against said call-circuit contact, there being recoil of said line-terminal contact against the opposing induction-coil contacts when the receiver aforesaid is taken from its hanger.
25. 6. An electric-telephone station equipped with the usual means for verbal communication, a calling mechanism, call-receiving mechanism and a vertical switch, the latter being electrically connected to its counterpart at each of a plurality of stations in the same system, a hanger for the receiver at each station vertically adjustable along the switch to connect the corresponding station with any other in the system for calling and talking purposes, and means whereby the hanger in normal position causes cut-in of the call-receiving mechanism simultaneously with a cut-out of the means for verbal communication, at the same station, the reverse being a result when said receiver is removed from said hanger which latter has direct return from any adjustment to said normal position by gravitation when the aforesaid receiver is hung thereon.
30. 7. An electric-telephone station equipped with the usual means for verbal communication, a calling mechanism, call-receiving mechanism and a switch, the latter being electrically connected to its counterpart at each of a plurality of stations in the same system, a hanger for the receiver at each station adjustable along the switch to connect the corresponding station with any other in the system for calling and talking purposes, means locking the hanger in adjusted position when the receiver is removed therefrom, restoration of said receiver resulting in direct automatic return of said hanger to normal position by

gravitation, and means whereby the aforesaid hanger in normal position causes cut-in of the call-receiving mechanism simultaneously with a cut-out of the means for verbal communication at the same station, the reverse being a result when there is separation of receiver and hanger.

8. A station equipped with an electric-telephone apparatus, a calling mechanism and a call-receiving mechanism, an adjustable hanger for the telephone-receiver, a locking means and an indicator with the hanger, and a selective switch operated by said hanger and electrically connected to a similar switch at each of a plurality of stations in the same system, whereby the movement of said hanger in an upward direction and removal of said receiver cuts in the desired station and locks the hanger in adjusted position, hanging up of the receiver serving to unlock the hanger and restore the switch to home stop directly by the action of gravitation.
- 15 9. A station equipped with an electric-tele-

phone apparatus, a calling mechanism and a call-receiving mechanism, an adjustable hanger for the telephone-receiver, locking means with the hanger, and a selective switch operated by the hanger and electrically connected to a similar switch at each of a plurality of stations in the same system whereby movement of said hanger in an upward direction and removal of said receiver cuts in the desired station and locks the hanger in adjusted position, hanging up of the receiver serving to unlock the hanger and restore the switch to home stop directly by the action of gravitation.

In testimony that I claim the foregoing I have hereunto set my hand, at Milwaukee, in the county of Milwaukee and State of Wisconsin, in the presence of two witnesses.

ROBERT H. YURGAE.
